QUICKLY REMOVABLE BOOT

Leslie H. L'Hollier, Waltham, Mass., assignor to
The B. F. Goodrich Company, New York, N. Y.,
a corporation of New York

Application March 27, 1941, Serial No. 335,430

5 Claims. (Cl. 36—50)

This invention relates to footwear and especially to quick-removable boots useful for example as aviators' boots.

Where flying operations are to be performed in extremely cold temperatures such as are encountered in cold climates or at high altitudes, it is necessary for the pilots, operators, and passengers, to wear heavy garments insulated against conduction of heat. Footwear suitable for such operations has usually been made of rubber and fabric or leather lined heavily with sheep wool or similar insulating material, and has been of such weight, especially when wet, as to have been a hazard to the wearer in case of a crash over water or where the operator has been forced to land in water, as by use of a parachute, as such footwear has been difficult to remove quickly.

The present invention aims to overcome the foregoing and other difficulties.

The principal objects of the invention are to provide quick detachability, as by a single pulling movement of a fastener to open the boot completely for removal from the foot, to provide security of fastening during wear, to provide accessibility of manipulating means, and to provide adequate protection to the wearer.

These and other objects will appear from the following description and the accompanying drawing.

Of the drawing:

Fig. 1 is a perspective view of an article of footwear embodying the invention, the fastening means being shown in secured position.

Fig. 2 is a similar view showing the fastener means in its opened position.

Fig. 3 is a perspective view of the handle means.

In accordance with the present invention, a warm heavy boot suitable for use in aviation is formed with a vent or opening extending from near the sole to the top of the upper, and preferably in the region of the toe, the margins of the upper adjacent the vent are secured to the completely separable stringers of a separable fastener structure adapted to be closed by downward movement and to be opened and also detached by a single movement of a slider element upwardly toward the top of the upper, and handle means is provided for securing the slider in its lower or closed position and for quick manipulation by a single movement in opening the boot, which handle means preferably is detachably mounted also at its free end so as to be in

the most convenient position for being quickly grasped.

Referring to the drawing, the numeral 10 designates an article of footwear in the form of a low boot for use by aviators and generally comprising an upper having a short vamp 11 preferably of leather or cloth, and quarters 12 of pliable and preferably waterproof material, such as rubber or rubberized fabric, a one-piece toe and counter reinforcement 13 of waterproof material extending thereover to the height of the heel and providing a waterproof reinforcement, and a rubber sole 14 vulcanized to the upper. The entire article is lined with a sheared or un-sheared sheep leather lining 15 with the wool side turned toward the foot of the wearer to provide warmth. The upper is formed with a vent 16 extending from near the sole to the top of the upper and preferably at the front of the boot.

20 A separable fastener 17 has its flexible stringers 18, 19 secured to the upper along the margins defining the vent preferably by cement and sewed means, and a reinforcement 20 of soft leather is applied to the upper around the vent 25 as by stitched seams to reinforce the opening. A leather binding 21 is also applied over the top margin of the upper and is sewed thereto. Ankle stay strips 22 are also secured over the quarters to provide additional strength in that region. 30 These may be of leather and sewed to the quarters so as to extend diagonally from the counter portion to the vent reinforcement, the strip 22 extending under the counter reinforcement 13 and under the strip 20 and being secured there- 35 to by stitches. A tongue 23 preferably of soft leather having a lining of sheared or unsheared sheep leather is provided beneath the vent and is preferably secured to the upper along one of its vent margins as well as to the vamp at the 40 toe.

The slide fastener 17 is of a construction in which the fastener elements 24 are engaged or disengaged from each other by a slider element 25 having cam surfaces to manipulate the slider elements into inter-engaging relation, and in which the slider 25 may be completely separated from one of the stringers by endwise movement. The fastener is mounted on the boot in such relation that the fastener elements are engaged 50 by downward movement of the slider 25 toward the toe of the boot and disengaged by movement of the slider in the opposite direction or toward the top of the boot, the arrangement being such that by grasping the tab 26 of the slider and pulling the slider up the leg the fastener elements

are completely separated at the top as well as along the margins so that the boot may be doffed easily and quickly.

To provide against accidental opening of the fastener and to provide for maintaining a part in a position for ready manipulation thereof by the wearer, a strap 27 preferably of leather, has one end secured pivotally, as by a tubular rivet 28, to the tab of the slider, and the opposite end is removably secured to the upper at a position above the slider along the margin of the vent by snap-fastener elements 29, 30 secured to the strap and upper respectively and engageable with each other when the slider is at its lowest position, as shown in Fig. 1. The strap 27 is preferably made relatively stiff to provide a strut, and for this purpose the leather may be rolled between its ends to provide a tubular cross-section with its margins sewed together as at 31.

The strap is preferably bowed between its ends so as to stand clear of the upper, as shown in Fig. 1, providing a handle which may be grasped quickly by the wearer even with thick gloves on his hands for quick doffing of the shoes in an emergency such as landing in water. The fastening of the snap fastener element keeps the strap in bowed condition and holds the slider at its lowest position. A stop 32 attached to one of the stringers 18 prevents withdrawing the slider completely from that side of the fastener, and a guide element 33 at the top of the other stringer is employed for guiding the slider into fastener-element-engaging position when closing the boot.

In securing the boot after it is on the foot, the element 33 is inserted in the slider and the slider is pushed along the stringers to its lowest position where the strap handle is secured by means of the snap fastener elements. In doffing the boot, the wearer merely grasps the strap handle and pulls upwardly releasing the snap fastener and opening the vent completely by a single movement.

While it is preferred to have the vent opening in the front of the shoe where the fastener is located for convenient operation, such a vent may be located at a side of the article or at the heel if desired.

Variations may be made without departing from the scope of the invention as it is defined by the following claims.

I claim:

1. A quickly removable article of footwear comprising a foot covering having a vent extending from the region of the toe to the top of the covering, a fully separable slide fastener for said vent having inter-engageable fastening elements secured at opposite margins of the vent and a slider having means movably engaging said elements to open said vent completely by movement of the slider to the top of the upper and to close said vent by movement of the slider toward the toe of the article, said article having a strap-like handle fixed at one end to said slider and removably secured at its opposite end to the covering at a position above the closed position of the slider and near said vent in a position for ready grasping of the handle.

2. A quickly removable aviator's boot compris-

ing a foot covering having a vent extending from the region of the toe to the top of the covering, a fully separable slide fastener for said vent having inter-engageable fastening elements secured at opposite margins of the vent and a slider operable therealong and having means removably engaging said elements to open said vent by movement of the slider to the top of the upper and to open said vent by movement of the slider toward the toe of the article, said article having a strap-like handle fixed at one end to said slider and removably secured at its opposite end to the covering at a position above the closed position of the slider and near said vent, said handle being bowed to stand clear of the foot covering in its secured position for ready grasping of the handle.

3. A quickly removable boot for aviators and the like, said boot comprising a foot covering having a closed bottom over the sole and heel portions and an upper portion formed with a vent extending from the top of the upper toward the bottom of the boot, and a fully separable fastener for said vent having inter-engageable fastening elements secured at opposite margins of the vent, said fastener comprising manual slider means arranged and adapted to inter-engage said elements by movement of the slider means from the top of the boot toward its bottom and to disengage said elements completely by a single movement of the slider means toward the top of the boot.

4. A quickly removable boot for aviators and the like, said boot comprising a foot covering having a closed bottom over the sole and heel portions and an upper portion formed with a vent extending from the top of the upper toward the bottom of the boot, a fully separable fastener for said vent having inter-engageable fastening elements secured at opposite margins of the vent, said fastener comprising manual slider means arranged and adapted to engage said elements by movement from the top of the boot toward its bottom and to disengage them completely by a single movement of the slider means toward the top of the boot, and handle means for operating said slider means, said handle means extending outwardly from said covering in a manner for ready grasping by the wearer.

5. A quickly removable boot for aviators and the like, said boot comprising a foot covering having a closed bottom over the sole and heel portions and an upper portion formed with a vent extending from the top of the upper toward the bottom of the boot, a fully separable fastener for said vent having inter-engageable fastening elements secured at opposite margins of the vent, said fastener comprising manual slider means arranged and adapted to engage said elements by movement from the top of the boot toward its bottom and to disengage them completely by a single movement of the slider means toward the top of the boot, handle means for operating said slider means in its disengaging movement, and means other than the fastening elements temporarily securing said slider means to the boot in closed position against sliding movement and disengageable by operation of said handle means.

LESLIE H. L'HOLLIER.
